FIG. 1.

FIG. 2.

INVENTOR.
Herman F. Zink, Jr.

BY *Mildred Stone, Jr.*

ATTORNEY.

UNITED STATES PATENT OFFICE.

HERMAN F. ZINK, JR., OF CHICAGO, ILLINOIS.

TELEPHONE ATTACHMENT.

1,391,087.

Specification of Letters Patent. Patented Sept. 20, 1921.

Application filed February 9, 1920. Serial No. 357,163.

To all whom it may concern:

Be it known that I, HERMAN F. ZINK, Jr., a citizen of the United States, residing at Chicago, in the county of Cook and State of Illinois, have invented new and useful Improvements in Telephone Attachments, of which the following is a specification.

This invention relates to telephone attachments in the nature of a card displaying data which is useful to the subscriber of the phone, and its object is to provide a device of this kind embodying certain novel features to be pointed out in detail herein-after.

In order that the invention may be better understood, reference is had to the accompanying drawing forming a part of this specification, and in said drawing Figure 1 is a face view of the device in place on the transmitter of a telephone, and Fig. 2 is a face view of the device removed from the transmitter.

Referring specifically to the drawing, 5 denotes a disk of pasteboard or other suitable light and cheap material, provided with a central opening 6 so that it may be mounted on the neck of a telephone transmitter, back of the mouthpiece. On the 10 face of the disk is mounted a series of calendar leaves 7 which are shaped to cover the upper half of the disk and to clear the opening 6 so as not to interfere with the mounting of the disk on the transmitter. The 15 leaves 7 have eyelets 8 at one end by which they are strung on a flexible tongue 8^a carried by the disk. The tongue 8^a is bent over into the form of a hook to hold the leaves, and one leaf after the other may be removed 20 as the dates designated thereon expire. The leaves may also contain advertising matter such as the program for a moving picture theater, and the upper portion of the disk also contains an advertisement of said 25 theater, and other data as shown in Fig. 2.

On the lower half of the disk are mounted two pivoted pointers 9 and 10, respectively. The pointer 9 indicates on a dial 11 printed on the face of the disk, the figures or numerals on the dial being arranged in a circle and representing money values from five cents to one dollar, each numeral being greater by five than the next preceding numeral. The pointer 10 indicates on a curved row of numerals running from one to four and representing money values in dollars.

The purpose of the two pointers and the dials on which they indicate is to register and thus keep an account of nickel calls made so as to enable the subscriber to know at a glance how many nickels he has deposited. Each time a nickel is deposited, the pointer 9 will be moved one step, and after it has made one complete revolution to 65 register one dollar, the pointer 10 is set opposite the one dollar graduation of its dial. At the completion of a second revolution of the pointer 9, the pointer 10 is set opposite the two dollar graduation, and so 70 on. The subscriber can therefore tell at a glance how many calls have been made and how much money has been deposited.

The device is very simple and it can be made cheap enough for free distribution as 75 an advertising novelty.

I claim:

A telephone attachment comprising a disk having means for attachment to the transmitter mouthpiece, a pivoted pointer carried by the disk, a dial of numerals on the disk for said pointer, and a second pivoted pointer and dial therefor on the disk to indicate the number of complete revolutions of the first mentioned pointer, said pointers being independently and manually operable.

In testimony whereof I affix my signature.

HERMAN F. ZINK, JR.
